UNITED STATES PATENT OFFICE

JAMES MUIR, OF PROVIDENCE, RHODE ISLAND, ASSIGNOR TO THE PHENIX IRON FOUNDRY, OF SAME PLACE.

CLOTH-STRETCHING MACHINE.

SPECIFICATION forming part of Letters Patent No. 527,441, dated October 16, 1894.

Application filed October 31, 1893. Serial No. 489,665. (No model.)

To all whom it may concern:

Be it known that I, JAMES MUIR, a citizen of Great Britain, residing at Providence, in the county of Providence and State of Rhode Island, have invented certain new and useful Improvements in Cloth-Stretching Machines; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to tentering frames, my object being to provide more effectual means for stretching the fabric, and it consists in a novel joint for the tenter rails; and also in various details of construction and 20 arrangement of parts as will be hereinafter described and referred to in the appended claims.

In the accompanying drawings illustrating my invention, Figure 1 is a side elevation of 25 a portion of a tentering frame showing my improved joint. Fig. 2 is a cross sectional elevation of a portion of a machine to which my invention is applied. Fig. 3 is an elevation in detail of the pivot plate used in the 30 joint. Fig. 4 is a plan of the same. Fig. 5 is an elevation in detail of the tenter rails at the joint; and Fig. 6 is a plan of the same.

In the drawings, D represents one of the standards of a tentering frame from which 35 extend the usual cross arms A, and along each of these is adjustable a saddle C upon which the rails C², C³ are supported. Motion is transmitted to the saddles by means of screw threaded shafts B suitably supported 40 by the cross arms and entering threaded openings in the saddles, motion being given to all the threaded shafts by means of worm wheels C¹¹ fastened upon them by keys C¹² and meshing with corresponding gears C¹⁰ 45 upon a power shaft E which extends the length of the frame.

Upon the saddle C is a plate C' pivoted thereto through the opening C⁷ and provided near each end with a lug C⁶ which lugs enter 50 cavities, C⁴, C⁵, provided therefor in the end of a tenter rail, thus pivoting each rail at its

ends to one of the plates C'. To prevent these rails from becoming vertically disarranged, tongues C⁸ project from one rail and enter recesses C⁹ in the abutting end of the adjacent rail, sufficient distance being left between neighboring rails, and the recesses C⁹ being sufficiently large to permit a single rail, as C², to be swung upon the pivot entering its cavity C⁴ without interference with an adjacent rail, as C³.

Many forms of ways for the tenter hook chains may be employed, but I prefer to use that illustrated. In this construction an angle plate F fits upon the rail C², one part of 65 said plate being raised a distance to admit the passage of the chain and then extending over the chain substantially parallel with the rail proper. This angle plate is adjustably secured to the rail by means of a bolt 70 F² passing through an opening in the angle plate, thus making it possible to use the same frame with various thicknesses of chains. A lip F' may depend from the top of the plate F and this together with the plate G serves 75 to prevent the chain from falling out of the way. The plate G is also made adjustable vertically to accommodate different sizes of chains, but chiefly to permit of the chain being removed by simply unfastening the plate 80 and withdrawing the chain from the recess in the angle plate F.

From the foregoing it will be seen that an extremely simple and readily adjustable way is provided for the tenter hook chain, but the 85 chief advantage of my frame lies in the use of the pivoted rail joint. All of the saddles may be adjusted by giving power to the shaft E, while should it be desired to further adjust any particular rail, the keys C¹² upon the 90 shafts passing through the saddles carrying the rail may be withdrawn and the saddles then moved by a crank applied to the ends of the shaft, the particular pivot joint described giving free movement at the point of 95 juncture.

Having thus described my invention, what I claim as new, and desire to secure by Letters Patent, is—

1. A joint for tenter rails, comprising an 100 adjustable support, a separate pivot pin upon said support for each rail to be supported,

and rails fitting upon said pivot pins; substantially as described.

2. A joint for tenter rails comprising a support, a plate pivoted upon said support, pivot pins upon said plate, and rails fitting upon said pivot pins; substantially as described.

3. A joint for tenter rails comprising an adjustable support, a plate pivoted upon said support, pivot pins upon said plate, and rails fitting upon said pivot pins; substantially as described.

4. A joint for tenter rails comprising an adjustable support, pivot pins upon said support, rails fitting upon said pivot pins and means for preventing vertical displacement of the rails; substantially as described.

5. A joint for tenter rails comprising an adjustable support, pivot pins upon said sup-

port, rails fitting upon said pivot pins one of said rails having a recess formed therein, and a tongue upon the other rail loosely fitting in said recess; substantially as described.

6. A tenter rail joint comprising an adjustable support, a plate pivoted to said support, pivot pins upon said plate, rails fitting upon said pivot pins, one of said rails having a recess formed therein, and a tongue upon the other rail loosely fitting in said recess; substantially as described.

In testimony whereof I affix my signature in presence of two witnesses.

JAMES MUIR.
